UNITED STATES PATENT OFFICE.

JAMES WATERFIELD, OF PHILADELPHIA, PENNSYLVANIA, ASSIGNOR TO QUAKER LACE COMPANY, OF PHILADELPHIA, PENNSYLVANIA, A CORPORATION OF PENNSYLVANIA.

LACE FABRIC AND METHOD OF MAKING SAME.

1,110,845.

Specification of Letters Patent. Patented Sept. 15, 1914.

Application filed September 2, 1913. Serial No. 787,702.

To all whom it may concern:

Be it known that I, JAMES WATERFIELD, a citizen of the United States, residing in the city of Philadelphia, State of Pennsylvania, have invented certain new and useful Improvements in Lace Fabrics and Methods of Making Same, of which the following is a full, clear, and exact description, reference being had to the accompanying drawings, forming a part of this specification.

My invention relates to lace fabrics, such as lace curtains, wherein a two-ply border, made by folding over the edge on itself, in imitation of a hemstitched border, is produced along one or more of its edges, and a supplemental lace edge afterward attached thereto by sewing.

The object of my invention is to make such a two-ply bordered curtain in imitation of a hemstitched edge fabric, but with an integral lace edge, and to produce it from an initially single ply fabric having the features of construction hereinafter described, by a folding over and stitching method, whereby there is produced on the finished curtain an edge commonly called a lace edge which is integral with the border proper and is formed by the fold in the production of the two-ply border.

To these ends my invention consists essentially in the production primarily of a blank, so-called, wherein the curtain border is composed of two integrally connected and reversely joined lace-forming portions which are identical and which, when folded one on the other and in register, and held by a line of stitching produce the integral lace edge desired; and in one embodiment of my invention such duplicated lace-forming portions constitute, in the blank, a border which is initially intermediate and parallel with a pair of border portions each composed of the usual curtain netting and which are utilized in forming the two-ply edge hence producing an additional finish and effect.

In the accompanying drawings illustrating my invention, Figure 1, Sheet 1, is a plan view of a blank so-called, from which the finished product is produced by my method and means; Fig. 2 is a like view of the finished curtain produced from such a blank; Fig. 3 is a section on line 3—3 of Fig. 2; and Fig. 4 a like section on line 4—4 of same Fig. 2. Figs. 5 and 6 illustrate a modified form of the invention, Fig. 6 being

a plan view of the finished article made from the blank shown in Fig. 5.

Referring now to said drawings, the blank so-called shown in Fig. 1 consists of the body portion of the curtain, indicated at 1, 1, which may be of any usual character and design surrounded by the narrow solid material indicated at 2, 2. The remainder of said blank involves the novel features and comprises essentially the lace forming strip 65 or portion composed of the duplicated identical parts 3 and 3, which together are to form, by the folding-over hereinafter described, the integral lace edge 6, 6 (see Fig. 2) of the finished product; and in any embodiment of my invention it is essential that this lace strip be composed of two integrally-connected parts, 3 and 3, which are identical and reversely joined, so that when folded over on the line of union, indicated by the dotted line b—b, in Fig. 1, they shall be in register and thus produce not only a lace edge but a serrated edge, both effects being due to the series of alining open work meshes 3', at regular intervals between 80 smaller openings 4 of like character. The ultimate two-ply border, in imitation of a hemstitched border and with integral lace edge may consist alone of this folded over duplex strip or portion 3, 3, as shown in the modification Figs. 5 and 6 but I prefer to add a supplemental border of netting indicated at 5 in Fig. 2, and this is produced in the blank by arranging the duplex lace-forming strip 3, 3, between two identical 90 borders of netting, indicated at 8, 8, in Fig. 1 at both the bottom and one side of the curtain, with narrow edges 7, 7, of solid or selvage material, so that when the border, as a whole, is folded over, the like elements will 95 be in register.

In producing the finished fabric, shown in Figs. 2 and 6 from the blank shown in Fig. 1 and the blank shown in Fig. 5, respectively, the corner of the latter is cut away on the dotted line a—a of said Fig. 1 and of Fig. 5, so that the corner may be suitably mitered. If then the outer netting supplemental border 8 is folded over on the like inner border 8, the selvage edge 7 will overlap the curtain body selvage or solid material edge 2 and a line of stitching indicated at 9, 9, is then applied along and through said selvage edges to fixedly secure the parts together, and an additional line or 110

lines of stitching may be applied if desired wherever such selvage or solid material edges overlap each other throughout the finished curtain. This folding over described 5 will obviously bring one of the supplemental netting borders 8 over the other one, and form the two ply border indicated at 5 in Fig. 2 and in Fig. 6 and in like manner produce the two-ply lace edge, indicated at 10 6 in said Fig. 2 and in Fig. 6, integral with the supplemental netting border 5 or with the curtain body 1 if as illustrated in Figs. 5 and 6 said netting border be omitted. Where the blank is constructed as shown, 15 that is to say with the two-ply border-forming and lace-forming edge elements along the basal edge as well as along one long side of the curtain, the folding over in the manner described will give a three-ply thickness at the mitered corner 10, but 20 not elsewhere.

The advantages resulting from producing a lace-edged two-ply bordered curtain or the like in the manner described are, in 25 addition to decreased cost, the integral character of the lace edge and durability and attractiveness of the resultant finished fabric.

Having thus described my invention, I 30 claim as new and desire to secure by Letters Patent:—

1. The method described of producing a two-ply bordered curtain with integral lace edge, which consists in first making a single 35 ply blank wherein a border portion is pro-

vided consisting of duplicated and reversely arranged formation of the lace edge, then bringing all of said duplicated elements into register with each other by a folding of one on the other, and finally applying 40 a line of stitching to secure them together.

2. The method described of producing a two-ply bordered curtain with integral lace edge which consists first making a single-ply blank with a border portion consisting 45 of a duplicated and reversely arranged formation of the lace edge interposed between and in parallelism with duplicated like courses of netting, each of said courses having a selvage edge; then bringing all of 50 said duplicated elements into register by a folding of one on the other, and finally applying lines of stitching to secure them together along said selvage edges.

3. An article of manufacture which consists of a single ply curtain body having a two-ply border formed by duplicated and reversely arranged lace portions, superimposed one on the other, all in register, secured together by stitching and forming 55 thereby a lace edge integral with said border.

In testimony whereof, I have hereunto affixed my signature this 31st day of July A. D. 1913.

JAMES WATERFIELD.
